UNITED STATES PATENT OFFICE.

ALBERT F. STAPLES, OF BROCKTON, AND CHARLES W. POTTER, OF WALTHAM, MASSACHUSETTS, ASSIGNORS TO THE McCASKEY REGISTER COMPANY, OF ALLIANCE, OHIO, A CORPORATION OF OHIO.

ACCOUNT-REGISTER.

No. 853,651.

Specification of Letters Patent.

Patented May 14, 1907.

Application filed February 26, 1906. Serial No. 302,879.

To all whom it may concern:

Be it known that we, ALBERT F. STAPLES and CHARLES W. POTTER, citizens of the United States, residing at Brockton and Waltham, respectively, in the counties of Plymouth and Middlesex, respectively, and State of Massachusetts, have invented certain new and useful Improvements in Account-Registers; and we do hereby declare the following to be a full, clear, and exact description of the invention, such as will enable others skilled in the art to which it appertains to make and use the same.

This invention relates to improvements in account registers.

The object of the invention is to produce an improved account register for use in connection with the system of accounting in which bills or charge slips containing the several accounts to be kept are filed in compartments of a bill file or register, and the invention consists in a bill file or account register, of the form in which the bills are secured to a number of pivotally mounted frames, embodying certain improvements in construction and operation hereinafter pointed out in connection with the description of the illustrated embodiment of the invention.

In the drawings Figure 1 is a side elevation of the invention, partly in section and Fig. 2 is a similar view on a smaller scale showing the position of the parts when the register is in use. Fig. 3 is a horizontal section with the frames removed, and the front cover drawn down. Fig. 4 is a perspective detail view of the devices for connecting the frames with a motion-controlling mechanism. Figs. 5 and 6 are detail views of the electric contact device.

The illustrated embodiment of the invention comprises a number of frames provided with clips for holding bills, a casing in which the frames are mounted and are inclosed when not in use, and mechanism within the casing for controlling the motion of the frames when they are open or shut to facilitate the use of the device and to prevent jar in opening and closing the frames.

The frames 1 are constructed of metal and provided with marginal flanges 2 to secure the necessary stiffness. They may also be provided with flanges 3 as shown in Fig. 4 to

divide them into separate compartments for the bills and to further stiffen them. The frames are provided with clips 4 of ordinary form for holding the bills on opposite sides of the frames. The frames are not hinged or pivoted to a supporting member, as is usual in devices of this character, but are fastened together by hinges 5 at the bottom, the hinges being located at the junctures between the bottom flanges of the frames, and the frames are all of the same size. The frames are thus hinged together in series and owing to this construction when folded together make a body of compact form as shown in Fig. 1, the frames being all parallel and none of them extending beyond the others. In this form, the frames may be conveniently removed from their casing as is sometimes desirable in order to put them with the bills contained therein in a safe or vault when not in use. Since the frames are hinged together in the manner above described, a single support for the bottom of the body of frames is sufficient, it being unnecessary to support each frame separately in the casing. The first or front frame therefore is provided with pivotal supports in the casing while the remainder of the frames, being supported at the bottom by the front frame, are left free at the bottom and are merely supported at the top to maintain them normally in upright position. When one or more of the frames is drawn forward and down to permit access to the bills, the frames drawn down assume the position shown in Fig. 2, remaining still parallel, while the remaining frames are raised and the bottoms drawn forward.

In order that the tops of the frames remaining upright may be moved forward, when some of the frames are drawn down, to the same extent as the bottom of the upright frames, means are provided to move the tops of the frames forward as the bottoms are moved forward and raised so that the upright frames are brought to a position parallel to their original position and the foremost upright frame is always at the same angle with the eye of the person using the device. To this end, the last frame is provided with rollers 50 journaled to the upper corners of the frame on a rod 6 fixed to the top of the frame. These rollers engage metal strips 7

fixed to the lower side of a cover 8 forming part of the casing. The cover 8 is hinged at 9 to the back 10 of the casing, and when the register is in use the cover 8 is swung upward 5 to the position of Fig. 2, being retained in this position by metal links 11 pivoted at their upper ends to the cover 8 and having slotted portions engaging screws 12 in the sides 13 of the casing. As the frames are 10 turned down the remaining upright frames, owing to the hinged arrangement of the frames are always raised and drawn forward through substantially the same distances, whatever may be the number of frames turned down, and thus by arranging the cover 8 at an angle of substantially 45° with the horizontal, the tops of the frames are moved forward by the rollers 50 through the same distance. It should be noted that by 15 this construction not only are the upright frames kept always substantially at the same angle but also they are brought forward, no matter how many frames are turned down, so that the front frame of those remaining 20 upright occupies always substantially the same position at the front of the cabinet and this facilitates the use of the register since it obviates the necessity of reaching into the casing as in previous account registers.

30 The front cover 14 of the casing is hinged at 15 to the front of the casing so that it may be swung down into the position shown in Fig. 2, in which it is retained by chains 16 fixed to the cover of the casing. In this position it serves as a desk upon which entries 35 may be made upon the bills and also as a support for the frames which have been turned down. The index of the accounts is also mounted upon the inner surface of 40 this cover so that when the cover is turned down the index is presented to view and when the cover is closed the index is concealed within the casing. The cover 14 is provided with a spring catch 17 which engages a catch 18 on the cover 8 when the 45 covers are both closed and serves to hold the covers closed. By means of a button 19 the catch can be released to open the covers.

Within the lower part of the casing mechanism 50 is provided for controlling the motion of the frames so as to facilitate turning them down and also to prevent them from jarring when quickly opened or closed. A rock shaft 20 is journaled transversely of the 55 casing, and is provided with depending arms 21 to which springs 22 are attached. The springs are adjustable being secured to eyes 23 having screw threaded shanks 24 entering nuts 25 in the back of the casing. The shaft 60 20 carries an arm 26 to the lower end of which is pivoted a link 27 having a cross pin 28 at its upper end. The cross pin 28 engages notched lugs 29 fixed to the bottom of the last frame and is held in engagement with 55 the lugs by a hook 30 pivoted to one of the

ribs 3 of the frame as shown particularly in Fig. 4. The springs 22 tend constantly to swing the arms upward whereby the weight of the frames is partly counter-balanced by the springs and less effort is required to draw 70 the frames forward and downward. As more and more of the frames are drawn forward, or as the frames in a body are drawn further and further forward, the arm 26 swings farther upward and the springs 22 in 75 contracting diminish their tension, so that by properly proportioning the springs and the mechanism connecting them with the frames, the counter-balancing effect of the springs is made to diminish substantially in 80 proportion as the necessity for the counter-balancing decreases as the frames are turned downward.

To prevent jarring when the frames are tipped back into the casing the arm 26 is connected with a piston rod 31 carrying a piston 32 which moves in a cylinder 33 journaled in brackets 34 in the casing. The piston is provided with a cup leather 35 which allows air to pass freely as the piston moves toward the 85 open rear end of the cylinder but prevents air from escaping as the piston is moved in the opposite direction. An adjusting screw 36 with a slotted shank provides an adjustable leak to permit the air to escape slowly from the 90 cylinder. Owing to the relative position of the cylinder and the arm 26 the piston moves from right to left during the first part of the movement of the frames and opposes no resistance to the movement of the frames, but 95 after the arm 26 is swung beyond the position in which it is in line with the pivotal supports of the cylinder 33 the direction of motion of the piston 35 is reversed and it then acts as a check upon the movement of the 100 arm 26 and of the frames so that by the cushioning effect of the air the frames are prevented from falling heavily upon the cover 14. A similar result is secured in returning the frames to the casing, the piston first moving 105 from right to left and then moving in the opposite direction and preventing the frames from striking heavily against the back of the casing. As a further precaution against jarring rubber buffers 51 are fixed in the back of 110 the casing in position to engage the flanges on the edges of the back frame, and rubber buffers or abutments 38 are fixed to each of the frames so that they do not jar against each other.

In order to provide an alarm to indicate the fact that the account register has been opened an electric contact device is mounted within the case. This contact device comprises a flat metal spring 58 pivotally mounted at its rear end in a recess in the side of the casing and tending normally to engage a contact piece 39 on the casing. The forward end of the spring 58 is provided with a beveled lug 40 adapted to engage a lug 41 on the edge 115 120 125 130

of the front frame. While the front frame is closed the spring 58 is held inward away from the contact piece 39 and the electric circuit is open. When the front frame is opened the 5 spring 58 closes the electric circuit. An electric battery 42 located within the casing and connected in a circuit with the contact making device, as shown in Fig. 3, thereupon causes a bell located in any convenient position to ring, the bell being connected with wires 43, Fig. 3, which pass out through the back of the casing. By this arrangement an alarm is given in case of any unauthorized tampering with the register. To prevent the 10 bell ringing continuously while the register is in use the spring 58 may be swung upward out of contact with the contact piece 39 after the first frame has been opened.

As it is desirable to have the frames readily 20 removable from the casing so that they may be put into a vault or safe when not in use, the pivotal supports for the front frame are made in the form of bearing blocks 44 fixed to the sides of the casing and having depressions in their upper sides loosely engaged by pins 45 projecting from the lower corners of the front frame. When it is desired to remove the frames from the casing they are drawn down upon the cover 14 and disengaged 25 from the link 27 by disengaging the hook 30 from the pin 28. The frames may then be lifted free from the blocks 44 and removed from the casing. The link 27 is provided with a lug 46 adapted to engage a pin 30 35 fixed to the arm 26, and a spring 48 mounted on the arm 26 engages the link 27 and tends to swing it downwardly until the lug engages the pin. The pin is so adjusted that when the frames have been removed as above 40 described the link 27 is held by the pin and the spring 48 in the correct position to be engaged again by the devices by which it is connected with the frame, so that in inserting the frames again it is necessary merely to insert the pins 45 in the notched blocks 44 and then press down the hook 30 to secure the 45 pin 28 in the lug 29.

The hinged arrangement of the frames and their normally parallel position have several 50 important advantages. By this arrangement the maximum capacity is provided in a minimum bulk, a feature which is especially important when the frames are to be stored in a safe. Another advantage resulting from 55 this construction is the fact that when several frames are drawn down there is no relative motion between the frames, and the bills held between them are therefore subjected to no danger of injury such as might occur in 60 other forms of account registers when the quantity of bills contained between the frames is sufficient to cause the bills on the adjacent surfaces of the frames to be in contact. It should be noted that owing to the 65 hinged arrangement of the frames the weight

of the frames remaining vertical, so far as it is not counter-balanced by the counter-balancing devices above described, has a tendency to cause the return of each horizontal frame to upright position, as soon as the 70 frame is swung upward slightly above horizontal position, so that the raising of the frames is facilitated to the same extent as if each frame were provided with springs to raise it, as in previous account registers. 75 This construction is much simpler than the previous construction since this effect results from the weight of the frames alone and no springs are necessary for this purpose.

Any convenient number of frames may be 80 used, and the use of counter-balancing and checking mechanism for the frames, or other motion controlling devices, is not essential to the invention in its broader aspects, although such devices contribute to the utility 85 of the invention.

The invention is not, in general, limited to the details of construction and operation of the illustrated embodiment, but may be embodied in other forms broadly defined in the 90 claims.

Having now described the invention, what is claimed is:—

1. An account register, having, in combination, a plurality of pivotally mounted 95 frames, means for supporting the frames normally in upright position, and means acting, when one or more frames are drawn down, to move the remaining frames forward to a position substantially in the plane normally occupied by the first frame, substantially as described.

2. An account register, having, in combination, a plurality of frames hinged together at the bottom, means for holding the frames 105 normally in upright position, and means acting, when one or more of the frames are drawn down, to move the tops of the remaining frames forward substantially the same distance that the bottoms are moved forward, substantially as described.

3. An account register, having, in combination, a plurality of frames pivotally connected together at the bottom, means for supporting the frames normally in upright position, and inclined guides co-operating with the last frame so as to cause the top of said frame to be moved forward as it is raised, substantially as described.

4. An account register, having, in combination, a plurality of frames hinged together at the bottom and provided with abutments holding the frames normally in substantially parallel position, pivotal supports for the first frame, means for holding the frames 125 normally in upright position, and means for moving the tops of the frames forward as the bottoms are moved forward in turning down the frames, substantially as described.

5. An account register, having, in combi- 130

nation, a plurality of frames hinged together at the bottom in series, pivotal supports for the first frame, means for normally supporting the frames in upright position, and yielding means opposing the upward movement of the frames for partially counter-balancing their weight, substantially as described.

6. An account register, having, in combination, a plurality of frames hinged together at the bottom, means for normally supporting the frames in upright position, pivotal supports for the first frame, and a counter-balancing device connecting with the last frame and subjecting the frames to a counter-balancing force diminishing substantially in proportion to the number of frames turned down, substantially as described.

7. An account register having, in combination, a plurality of pivotally mounted frames, and a casing, in which the frames are normally supported in upright position, provided with a cover pivoted at the rear and having means for limiting its upward motion so as to act as a guide for the tops of the frames by engagement with the last frame when one or more of the frames are turned down, substantially as described.

8. An account register having, in combination, a plurality of frames hinged together, a casing provided with loose pivotal supports for the front frame arranged to permit the frames to be readily inserted therein and removed therefrom, and a motion-controlling device located in the casing and detachably connected with the frames, substantially as described.

9. An account register having, in combination, a plurality of frames hinged together in series, a support for the frames, and a single counter-balancing means for the frames connected with one of the terminal frames, substantially as described.

10. An account register having, in combination, a plurality of frames hinged together in series, a pivotal support for one terminal frame, and counter-balancing means connected with the other terminal frame at its hinged edge, substantially as described.

11. An account register having, in combination, a plurality of frames hinged together

in series, a support for the hinged edges of the frames and means for moving the remaining frames, as one or more of the frames is swung about its hinges to cause them to remain substantially parallel to their original positions, substantially as described.

12. An account register including a case having a back, a pair of pivotal supports in the case, and a plurality of bill holding frames hinged to each other, the foremost 65 one of said frames being pivotally mounted in said pivotal supports and supporting the other frames, all of the frames when upright being inclined to lean by gravity toward the back of the case.

13. An account register including a case having a back, a pair of pivotal supports in the case, a plurality of bill-holding frames hinged to each other, the foremost one of said frames being pivotally mounted in said pivotal supports and supporting the other frames, all of the frames when upright being inclined to lean by gravity toward the back of the case, and compensating paralleling apparatus in the case acting, when one or more of the frames are drawn down, to assist in moving the remaining frames forward to positions approximately parallel to the plane normally occupied by the foremost frame.

14. In account registers, the combination 80 with a cabinet case, and a plurality of bill-holding frames hinged one to another and collectively forming a connected portable group of frames, of a pair of pivotal supports mounted in the case and pivotally supporting the forward part of the forward one of the frames and thereby supporting the group of frames, the frames being movable separately in succession to either upright or reclining positions, and means in the case to be engaged by the rearmost frame for holding it upright when bodily elevated and a forward frame reclines.

In testimony whereof we affix our signatures, in presence of two witnesses.

ALBERT F. STAPLES.
CHARLES W. POTTER.
